Fig. 1

Fig. 3

Fig. 2

Fig. 1 is a front elevational view of an advertising sign showing my new design, the rear being substantially like the front shown and the dot-dash representation of a support being for illustrative purposes only.

Fig. 2 is a top plan view thereof taken perpendicular to the top of the pole.

Fig. 3 is a right side elevational view thereof taken perpendicular to the length of the pole.

I claim:

The ornamental design for an advertising sign, as shown and described.
